UNITED STATES PATENT OFFICE.

CHARLES F. STRASBURG, OF LINCOLN, NEBRASKA.

TROLLEY-WIRE HANGER.

SPECIFICATION forming part of Letters Patent No. 519,621, dated May 8, 1894.

Application filed August 31, 1893. Serial No. 484,517. (No model.)

To all whom it may concern:

Be it known that I, CHARLES F. STRASBURG, a citizen of the United States, residing at Lincoln, in the county of Lancaster and State of Nebraska, have invented new and useful Improvements in Trolley-Wire Hangers, of which the following is a specification.

My invention relates to that class of devices commonly termed trolley-wire hangers, or clamps, for sustaining and insulating overhead electric wires.

It is the purpose of my said invention to provide a trolley-wire clamp formed in a single piece, having the maximum strength required and of the minimum weight, or mass, of metal, the construction being such that a smooth and practically uniform surface shall be presented to the trolley-wheel, where sparking and the burning out of the trolley wire and clamp shall be prevented.

It is a further purpose of my invention to provide a trolley-wire clamp so formed that it may be caused to fit closely around the wire without materially straining the metal of the clamp, and make a smooth, firm, and permanent union of the parts having greater strength and durability with materially less metal and consequent reduction of weight, as compared with the clamps of this type now in use.

It is a further purpose of my invention to provide a trolley-wire clamp with a lug, whereby it may be connected to the insulator, the construction being such as to permit the connection to be readily made with any ordinary form and size of insulator, without the use of screws which are liable to work loose and become detached.

To these ends my invention consists in the several novel features of construction and in the parts and new combinations of parts hereinafter fully described and then more particularly pointed out and defined in the claims which conclude this specification.

To enable those skilled in the art to which my invention pertains to make, construct and use the same, I will describe said invention in detail, reference being had to the accompanying drawings, in which—

Figure 1 is a perspective view of a trolley-wire clamp constructed in accordance with my invention. Fig. 2 is a central transverse section of the same. Fig. 3 is a side elevation, and Fig. 4 is an end elevation, showing the wire seated in the clamp and permanently secured in place.

In the said drawings the reference-numeral 1 indicates the body portion of the trolley-wire clamp, which is preferably formed of brass, though other suitable metal may be used. At, or about, the central point of the body portion 1 is formed a lug 2, which rises from the upper side to which it is braced by webs 3, of sufficient thickness to give the necessary strength and rigidity, without adding materially to the weight. The upper extremity of the lug 2 is forked, or formed with two similar portions 4, approximately rectangular in shape and having sufficient lateral projection to afford space between said portions for the insertion of the insulator, which will preferably be secured by means of a squared bolt inserted in an aperture 5, in one of the similar parts 4, its threaded end being passed through a circular opening in the other similar portion. In order to adapt the device to be used upon insulators of different forms and varying in size, I slot the lug 2 centrally, the cut being parallel with the length of the body-portion and extending into the upper portions of the webs 3, upon each side of the lug, as shown by the reference numeral 6, in Figs. 2 and 4. This slot enables the two similar portions 4 of the lug to be separated, within certain limits, or sprung apart, to admit an insulator of a size exceeding the normal space between said parts 4. On the other hand, also, a sufficient quantity of metal is removed, by the formation of the slot 6, to permit the portions 4 to be drawn together, under the force of the bolt and nut, in case the inserted insulator should be so small as to fit the space loosely.

The reference-numeral 7 indicates the groove or seat, in the body portion 1, for the reception of the trolley wire. This groove, which is co-extensive with the length of the said body-portion, is cut, or formed, of rect-

angular shape, or practically so, and is open upon the lower side, its two lateral faces being substantially parallel. The two lateral walls inclosing said groove are dressed off upon 5 their exterior surfaces to form slightly convex faces and bring the metal of said walls to a thin edge. At each end of the body-portion 10 the lateral walls are rounded off and the curved edges are dressed off, exteriorly, to 15 preserve a uniform thickness, or substantially so, throughout. When the trolley wire is seated, or inserted in the groove 7, the lateral walls are drawn together at and near their edges, thereby clamping the wire and permanently fastening it. The edges of the lateral 20 walls being drawn toward each other against the lower side of the wire, form a secure clasp without any practical interruption of the uniform surface upon which the trolley wheel 25 travels, thereby avoiding the "arc," or sparking, by which the connection would be speedily injured, and in time destroyed. The rounded extremities of the lateral walls, also, remove the abrupt angles by which a more or less defective contact would be caused, and also avoid the loss of current by leakage. 30 By employing the rectangular form of groove the wire can be more easily seated therein, the metal is more firmly clamped around the wire, the device is better adapted for use with wires of varying size, and the clamp, when closed up, will make a smooth and uniform contact surface for the trolley-wheel, which is not practicable where a circular groove is employed. By using a continuous groove, or seat, these results are ma- 35

terially promoted and all necessity for applying solder is avoided.

What I claim is—

1. A trolley-wire clamp having a rectangular groove or seat for the trolley-wire, substantially co-extensive with the body-portion of the clamp and continuous, substantially as described. 40

2. A trolley-wire clamp having a rectangular groove or seat, for the trolley-wire the two lateral walls inclosing said groove being rounded at their ends and dressed off to bring the metal to a thin edge, on each wall, substantially as described. 45

3. A trolley-wire hanger provided with a central lug having a forked end, said lug being centrally slotted longitudinally, the slot extending into the webs which brace and stiffen the lug, substantially as described. 50

4. A trolley-wire hanger having a body-portion which is provided with a rectangular groove or seat for the trolley wire and having a central lug rising from the upper side of said body portion, to which it is braced by integral webs, the forked upper end of the lug, being divided by a central longitudinal slot extending into the webs, substantially as described. 55

In testimony whereof I have hereunto set my hand in presence of two subscribing witnesses. 60

CHARLES F. STRASBURG.
